UNITED STATES PATENT OFFICE.

JOSE F. DE NAVARRO, OF NEW YORK, N. Y.

LOCOMOTIVE-BOILER.

No. 823,183.

Specification of Letters Patent.

Patented June 12, 1906.

Application filed March 3, 1905. Serial No. 248,279.

To all whom it may concern:

Be it known that I, JOSE F. DE NAVARRO, a subject of the King of Spain, and a resident of the borough of Manhattan, in the city and State of New York, have invented a new and useful Locomotive-Boiler, of which the following is a specification.

My invention relates to locomotive-boilers, the object being to provide a boiler of this type which shall be capable of burning pulverized fuel with great economy and high efficiency.

In the accompanying drawings, Figure 1 is a partial longitudinal vertical section through a boiler embodying my invention. Fig. 2 is a transverse section in the plane of the line A A, Fig. 1; and Fig. 3 is a horizontal section in the plane of the line B B of Fig. 1.

The boiler, so far as its external shape and general structure is concerned, may be any one of the locomotive-boilers at present in use, and one of the advantageous features of my invention is that it may be readily applied to boilers at present in use, as well as to those which may be especially built to embody it.

The outer shell of the boiler is denoted by 1. The general wall of the fire-chamber is denoted by 2, and the water-space between the shell 1 and fire-chamber 2 by 3. The water-space is continued down the sides and front of the fire-chamber, and the wall 2 is held in proper relation to the shell 1 by numerous tie-rods or rivets 4.

The group of fire-tubes leading from the front of the fire-chamber to the uptake is denoted by 5, and the steam-dome by 6.

The rear part of the fire-chamber is separated from the front part throughout a considerable portion of its height by a brick wall 7, which, starting at the bottom 8, extends upwardly and gradually curves over toward the rear end of the boiler, finally terminating at a point spaced from the top of the fire-chamber a distance sufficient to permit the products of combustion to pass into the front part of the chamber.

The brick wall 7 is supported by a series of water-tubes 9, which are secured at their upper ends in the rear wall of the fire-chamber at or near its top and curve downwardly and forwardly, housed within the brick wall 7, until they reach a point near the bottom 10 of the front part of the chamber and thence extend exposed along the said front part of the chamber to the front wall of the fire-chamber, where their lower ends are secured,

the said tubes 9 forming circulating connections between the water-spaces at the front and rear of the fire-chamber and at the same time a support for the wall 7.

To further strengthen the wall 7 and increase the water-circulating space, tubes 11, preferably alternating with the tubes 9, connect with the top wall of the fire-chamber over the top of the wall 7 and extend downwardly, following the curve of the wall 7 in proximity to the front of the wall and thence along near the bottom of the front part of the fire-chamber to their connection with the front wall of the chamber.

The bottoms 8 and 10 of the parts of the fire-chamber are brick-lined, and the bottom 8 is hinged at its front end at 12 to permit it to be dropped into the slanting position shown in dotted lines, Fig. 1, to provide for the ready removal of the light ash and sediment.

The pulverized fuel, mixed with air, is admitted at 13 through the rear wall of the fire-chamber and near the bottom thereof.

Above the fuel-entrance 13 a horizontal brick wall 14 is located and projects into the fire-chamber one-third of the distance, more or less, from the outer wall of the chamber to the brick wall 7 and is supported by a series of tubes 15, which connect with the rear or outer wall of the fire-chamber immediately below the wall 14 and after passing along beneath said wall bend upward and return to the outer or rear wall and are secured thereto.

An upright brick lining 16 extends from the bottom 8 up half the height of the outer or rear wall of the chamber, more or less.

The tubes 15 provide for water circulation from the water-space at the rear of the chamber, into the chamber, and back again.

Transverse water-circulating tubes 17 and 18 extend across the fire-chamber near the lower front face of the wall 7 to hold the tubes 9 and 11 in position and at the same time increase the water-heating surface.

In operation the fuel is ignited as it enters the rear part of the fire-chamber, and the mass of flame impinges against the wall 7 and is deflected by said wall upwardly and rearwardly, heating the wall 7 to a high degree and also the tubes 15 and tubes 9, the mass of flame passing thence over the wall 7 and in its course impinging against the top wall of the fire-chamber, then in passing through the front part of the fire-chamber coming into intimate contact with the tubes 11, 17, and 18 and with the walls of the fire-

chamber, and finally passing to the uptake through the group of fire-tubes 5.

The structure is a very efficient one for transmitting to the water the heat from the 5 mass of flame resulting from burning pulverized fuel in suspension and is so developed that it may be readily applied to locomotives at present in common use.

What I claim is—

10 The combination with the fire-chamber of a locomotive provided with a partition or baffle-wall intermediate of its ends and means

for directing pulverized fuel into the chamber, of a hinged bottom section to the rear of the said partition-wall for removing the ash 15 and sediment.

In testimony that I claim the foregoing as my invention I have signed my name, in presence of two witnesses, this 9th day of February, 1905.

JOSE F. DE NAVARRO.
